US0D1051161S

(12) **United States Design Patent** (10) Patent No.: **US D1,051,161 S**
(45) Date of Patent: ** Nov. 12, 2024

(54) **DISPLAY SCREEN OR PORTION THEREOF WITH GRAPHICAL USER INTERFACE**

(71) Applicant: **YAMATO SCALE CO., LTD.**, Akashi (JP)

(72) Inventors: **Masafumi Takimoto**, Akashi (JP); **Shigeyuki Takao**, Osaka (JP)

(73) Assignee: **Yamato Scale Co., Ltd.**, Akashi (JP)

(**) Term: **15 Years**

(21) Appl. No.: **29/772,096**

(22) Filed: **Feb. 26, 2021**

(30) **Foreign Application Priority Data**

(57) **CLAIM**

The ornamental design for a display screen or portion thereof with graphical user interface as shown and described.

DESCRIPTION

The sole FIGURE is a front view of a display screen or portion thereof with graphical user interface showing our new design.

The broken lines shown in the FIGURE illustrate the perimeter of a portion of a display screen and form no part of the claimed design.

1 Claim, 1 Drawing Sheet
